GALE L. FERGUSON, OF CLEVELAND, OHIO, ASSIGNOR, BY MESNE ASSIGNMENTS, TO
AUTO PRIME PUMP COMPANY, OF CLEVELAND, OHIO, A CORPORATION OF OHIO

PUMPING APPARATUS

Application filed November 9, 1927. Serial No. 232,037.

The present invention relates, as indicated, to a pumping apparatus, and more particularly to the rings adapted for insertion in the casings of centrifugal pumps. The primary objects of the invention are to provide against leakage from the liquid channel of such pumps, to provide the most efficient type of liquid channel, and to provide means for varying the capacity of a pump of given size. To the accomplishment of the foregoing and related ends, said invention, then, consists of the means hereinafter fully described and particularly pointed out in the claims.

15 The annexed drawing and the following description set forth in detail certain mechanism embodying the invention, such disclosed means constituting, however, but one of various mechanical forms in which the 20 principle of the invention may be used.

In said annexed drawings:

Fig. 1 is a cross-section of a pump of the type indicated disclosing a pump ring provided with sealing means; Fig. 2 is an elevation of a slightly modified ring; Fig. 3 is a transverse fragmental section of a pair of mating pump rings and an impeller; Fig. 4 is an elevation of a ring of small capacity; and Fig. 5 is an elevation of a ring of large 30 capacity.

Referring more particularly to Fig. 1, the reference numeral 1 indicates a pump casing having an inlet connection 2 and an outlet connection 3. Said casing provides a cylindrical chamber 4 housing a pair of pump rings, only one of which is shown at 5.

Each of these rings comprises an outer rim 6 provided with an inlet port 6' and an outlet port 6" communicating with a liquid channel 7, and said channel is separated by a land 8 from the bearing aperture 9 in which is mounted the hub of an impeller 10. Said impeller comprises a disc-like element 45 formed, on its periphery, with a plurality of buckets 10' and 10", alternate ones of said buckets opening through opposite sides of said impeller. It will be noted that each of said buckets is formed with a curved inner 50 wall tending to increase the centrifugal effect

of the rotating impeller upon the liquid in the channel 15.

The above elements are disclosed in my copending application, Serial No. 225,888, filed October 13, 1927. Experiments have 55 shown that, in the operation of such pumps, a certain amount of leakage occurs between the land 8 and the adjacent face of the impeller 10. It is obvious that leakage occurring here causes a tendency toward equalization of pressures in the liquid channel 7, thereby lowering the efficiency of the apparatus. The grooves 11 in said land are provided to prevent such leakage. The grooves 11 are, as is clearly indicated in Fig. 1, inclined outwardly in the direction of rotation of the impeller, and their inner ends 12 are closed, while their outer ends 13 open into the channel 7. It will further be obvious that the grooves are so positioned that a radius drawn 60 from the center of the ring and cutting the closed end of one groove will also cut the open end of an adjacent groove. Any liquid which seeps between the land 8 and the adjacent face of the impeller 10 will eventually 65 find its way into one of the grooves 11. The liquid in the channel 7 rushing past the open end of said groove will have an ejector effect tending to draw the liquid in said groove 70 out into the channel. Furthermore, because 75 of the inclination of said grooves, the wiping effect of the impeller will tend to force the liquid out of the grooves and into the channel 7. Moreover, the liquid in the grooves 80 acts as a liquid seal to prevent any flow into 85 the bearing aperture 9.

Fig. 2 illustrates a modification in which the inner ends of the grooves 11' are joined by a part-annular groove 14. Said groove 14 provides merely an added safeguard 90 against leakage into the bearing aperture 9'.

In Fig. 3 I have shown the cross-sectional shape of the liquid channel formed by mating rings 5 and 5'. This channel, as will be 95 obvious, is formed by the grooves 7 and 7' in the mating rings, and it will be noted that the outer portion 15 of the channel is narrower than the inner portion 15. The channel is so formed to prevent the occurrence of eddy currents in the channel which might 100

be set up by the slight differences in the velocity of various portions of the liquid stream. It will be quite obvious that that portion of the liquid stream which is farthest removed from the center of rotation of the impeller 10 will have a higher velocity than that portion which is nearer said center of rotation, and consequently that a channel of smaller cross-section will suffice for the passage of an equal volume of liquid. The shape of the channel is exaggerated in Fig. 3, but the important fact is that the channel is so designed that substantially equal volumes of liquid will flow through each horizontal section of said channel as viewed in Fig. 3.

Figs. 4 and 5 illustrate pump rings of separate sets which may be used with a single casing. Quite often it is desirable to vary the capacity of a pump; that is, a pump may be used in such a relation that, at certain times, it is necessary to pump a large volume of liquid for a relatively long time, and at other times it is necessary to pump only a relatively small volume of liquid for a considerable period. In such a case, it is necessary, of course, to install a pump which can handle the large volume when necessary, but it is wasteful of energy to use the large capacity pump to supply a relatively small volume of liquid. One of the objects of the present invention is to provide means for obviating this extravagance.

A single pump installation will include a single casing, a single impeller, and a plurality of pairs of pump rings of uniform external and internal diameters for selective insertion in said casing. Fig. 4 illustrates one ring 5^a of such a pair having a land 8^a of relatively great width, and consequently having a channel 7^a of relatively small capacity. Fig. 5 illustrates a similar ring 5^b of another pair and having a relatively narrow land 8^b and a consequently wide channel 7^b. It will be quite obvious that if the ring 5^b and its mate be inserted in the casing 1, the pump will have a relatively high capacity, whereas if the ring 5^a and its mate be inserted in the casing 1, the pump will have a relatively low capacity.

Of course, it is to be understood that I might vary the inside diameters of the various pairs of rings to permit the use of impellers of various sizes, thus to provide for high and low speed rotation of the impeller, it being understood that high pressure and low volume are sometimes desirable, while at other times it is desirable to have low pressure and high volume.

Other modes of applying the principle of my invention may be employed instead of the one explained, change being made as regards the mechanism herein disclosed, provided the means as stated by any of the following claims or the equivalent of such stated means be employed.

I therefore particularly point out and distinctly claim as my invention:

1. A pump ring comprising an outer rim, an annular channel concentric with said rim throughout a part of its length but provided with inlet and outlet ports through said rim, a bearing aperture centrally located in said ring, a land dividing said channel from said aperture, and sealing grooves in said land.

2. In a rotary pump, a pair of mating rings each of which comprises a bearing aperture, a water channel, and a land dividing said channel from said aperture, an impeller journaled in said apertures, bearing on said lands, and extending into said channel, and sealing grooves in one of said lands.

3. In a rotary pump, a pair of mating rings each of which comprises a bearing aperture, a water channel, and a land dividing said channel from said aperture, an impeller journaled in said apertures, bearing on said lands, and extending into said channel, and a plurality of sealing grooves in one of said lands having their inner ends closed and their outer ends opening into said channel.

4. In a rotary pump, a pair of mating rings each of which comprises a bearing aperture, a water channel, and a land dividing said channel from said aperture, an impeller journaled in said apertures, bearing on said lands, and extending into said channel, and a plurality of sealing grooves formed in one of said lands at an angle to the radii of the ring.

5. In a rotary pump, a pair of mating rings each of which comprises a bearing aperture, a water channel, and a land dividing said channel from said aperture, an impeller journaled in said apertures, bearing on said lands, and extending into said channel, and a plurality of sealing grooves formed in one of said lands at an angle to the radii of the ring and having their inner ends closed and their outer ends opening into said channel.

6. In a rotary pump, a pair of mating rings each of which comprises a bearing aperture, a water channel, and a land dividing said channel from said aperture, an impeller journaled in said apertures, bearing on said lands, and extending into said channel, and a plurality of sealing grooves in one of said lands having their inner ends closed and their outer ends opening into said channel, the open end of each groove being in such a position as to be cut by a radius cutting the closed end of an adjacent groove.

7. In a rotary pump, a pair of mating rings each of which comprises a bearing aperture, a water channel, and a land dividing said channel from said aperture, an impeller journaled in said apertures, bearing on said lands, and extending into said channel, and a plurality of sealing grooves in one of said lands, one end of each groove being closed and the other end opening into said channel,

said grooves being inclined outwardly in the direction of rotation of said impeller.

8. In a rotary pump, a pair of mating rings each of which comprises a bearing aperture, a water channel, and a land dividing said channel from said aperture, an impeller journalled in said apertures, bearing on said lands, and extending into said channel, and a plurality of sealing grooves in one of said lands having their outer ends opening into said channel, and their inner ends connected by a part-annular groove.

9. In a rotary pump, a pair of mating rings each of which comprises a bearing aperture, a water channel, and a land dividing said channel from said aperture, an impeller journalled in said apertures, bearing on said lands, and extending into said channel, a plurality of sealing grooves in one of said lands, the outer ends of said grooves opening into said channel, the outer end of each groove being in such a position as to be cut by a radius cutting the inner end of an adjacent groove, and a closed, part-annular groove connecting the inner ends of said grooves.

10. In a rotary pump, a pair of mating rings each of which comprises a bearing aperture, a water channel, and a land dividing said channel from said aperture, an impeller journalled in said apertures, bearing on said lands, and extending into said channel, and a plurality of sealing grooves in one of said lands, the outer end of each groove opening into said channel, and said grooves being inclined outwardly in the direction of rotation of said impeller, and a part-annular groove connecting the inner ends of said grooves.

11. A pump comprising a casing, a pair of mating rings mounted in said casing and formed to provide an enclosed water channel having an inlet port and an outlet port, and an impeller mounted between said rings and extending into said channel, the outer portion of said channel being narrower than its inner portion.

12. A pump comprising a casing, a pair of mating rings mounted in said casing and formed to provide an enclosed annular water channel having an inlet port and an outlet port, and an impeller mounted between said rings and extending into said channel, said impeller being adapted to be rotated to impress a velocity upon fluid contained in said channel, the volume capacity of said channel varying inversely with the velocity attained by such fluid.

Signed by me this 2nd day of November, 1927.

GALE L. FERGUSON.
